Graham, deceased

Application January 27, 1938, Serial No. 187,214

7 Claims. (Cl. 197—165)

(Granted under the act of March 3, 1883, as
amended April 30, 1928; 370 O. G. 757)

The invention described herein may be manufactured and used by or for the Government for governmental purposes, without the payment to us of any royalty thereon.

This invention relates to printing telegraph machines and more particularly to the ribbon feed mechanism of such machines.

The invention supplements our previous applications, Serial No. 725,968 filed May 16, 1934, which matured as Patent No. 2,128,242, August 30, 1938, and Serial No. 102,178 filed September 23, 1936, which disclose an exactly synchronized printing telegraph system and new features in printing telegraph mechanism. The present invention proposes certain new ribbon feed mechanisms operatively coordinated with the devices previously disclosed.

One of the main objects of this invention is to provide a ribbon feed reversing mechanism in which a minimum of work is imposed upon the ribbon itself in the reversing process, and to perform the reversing operation by shifting the driving pawl from engagement with the driving ratchet of the full ribbon reel or spool to engagement with the driving ratchet of the empty ribbon reel or spool.

Another main object is to provide an independent transmission system for each ribbon reel and to transfer the drive from one transmission system to the other transmission system by means of the ribbon rivet located near the ribbon end.

Another main object is to provide ribbon driving means actuated in sinusoidal and uniform motion at the rate of one cycle for each and every complete operation of the transmitting receiving printing telegraph mechanism. As described in detail in our previous application Serial No. 102,178, upon the completion of the transmission and selection processes, which are held in exact unison by our reed driven escapement mechanism, a functional gang cam group is permitted to perform one revolution. A cam in this group delivers the power for the ribbon feed stroke.

Other important objects will become apparent to those skilled in the art.

Fig. 1 is a schematic diagram of our printing telegraph machine and incidental circuits which, while previously disclosed in our application, Serial No. 102,178, filed September 23, 1936, is re-

produced here by way of illustration of operative features comprising the present invention and other function performing instrumentalities of the system;

5 Fig. 2 is a bottom sectional view of the receiver or shuttle selector mechanism;

Fig. 3 is a sectional view of the track switch of the receiver or shuttle selector mechanism;

Fig. 4 is a front elevation of the ribbon feed mechanism;

Fig. 5 is a side elevation of the same;

Fig. 5a is a section on line x—x of Fig. 5; and

Fig. 6 is a plan view.

In Fig. 1, we represent schematically our printing telegraph machine terminated at the ground connection 2 and the line terminal L. The motor 223 drives shaft 135 continuously through bevel gears 224 and 134. The gang cam group 130 is at rest because the driven positive clutch member 131 is held out of engagement with the driving clutch member 132 by the clutch arm 137 against the tension of spring 133. Bevel gear 225, likewise in continuous rotation, drives gear 166 through gears 226 and 227. The vertical shaft 211 is pinned to gear 166 and is also in continuous rotation.

The vertical shaft 211 transmits drive to two friction clutches; one for the type wheel 152 at 206 and 207; and the other for the rotor of the shuttle selector 190, and through gear 228, the reed escapement and distribution shaft 165. The type wheel 152 is rotated from selected position to selected position; the stoppage of the type wheel at a selected position being caused by the interference of the pertinent stunt bar 214, selected by the alignment of slots in the translator code disks 215, in the path of the type wheel stop member 212. The rotation of the shuttle selector 190 and of the reed escapement and distribution shaft 165 depends upon the position of the reed 172 and its escapement yoke 175 with respect to the escapement pins 174a to 174f inclusive mounted on the escapement hub 174 which is pinned to shaft 165.

45 The reed 172 is clamped at 179 and, upon being released, vibrates between the dotted positions 172a and 172b in six half cycles of vibration from start to stop. The normal or start-stop position of the reed is at 172a under the latch 171 of the start-stop magnet 62.

The distributor 57 performs an automatic stop function in a local circuit on the reed start-stop magnet 62, switching the magnet from the control of the line relay 48 direct to battery at segment 60a and switching back to line relay 48 control at segment 60 during one revolution of distributor arm 58. The transmitting distributor 49, in the progression by reed escapement of the distributor arm 50 from segment 56 to segments 51, 52, 53, 54, 55 and return to 56, performs the function of step by step connection of the keyboard transmitting contacts 17, 18, 19, 20 and 21 to the line 1 through line relay 48.

The cams 243 and 244 on the extremity of shaft 165 in conjunction with the cam levers or arms 245 and 250, the link 253, the release-restore bar 256, and the keyboard universal bar 24 operating latch 260, perform the functions of release and restore of the transmitting contact levers 12, 13, 14, 15 and 16, the contact lever 22 being the start-stop feature which is normally held closed with respect to contact 22. The keys of the keyboard, of which one is shown as 32, operate to rock the code bars 25, 26, 27, 28 and 29 into marking or spacing positions in accordance with the permutations of the five equal unit code. The code bars in turn set the contact pawls 267, 268, 269, 270 and 271, in marking or spacing positions with respect to contact levers 12, 13, 14, 15 and 16. Upon the release of bar 256 the contact levers under spring tension will either make contact, or not make contact, with the transmitting contacts 17, 18, 19, 20 and 21, dependent upon whether or not a contact pawl is interposed in spacing position as shown in the figure.

The shuttle selector rotor 190 is in step-by-step relationship with the transmitting distributor arm 50 under the joint escapement action of reed 172 driving escapement yoke 175 to permit the progression of escapement pins 174a to 174f, inclusive. In one revolution of the rotor 190 the shuttle selectors 190a to 190e are assigned to either the marking track 189a or the spacing track 189b dependent upon whether the armature 66 is in marking or spacing position at the instant each particular shuttle selector passes the armature at the track switch.

The code bar translator is shown at 123, the permutation bars or slotted code bars being 125 and the transverse members or stunt bars at 214. The particular stunt bar at 214 is shown in selected position effecting the stoppage of type wheel 152 at the stop member 212.

The selector transfer assembly which transfers the established selection from the shuttle selector to operate upon the code bar translator at the proper time is the transfer frame 192 carrying the five transfer cams 192a to 192e. Upon downward movement of the transfer assembly, the transfer cams 192a to 192e, are set in marking or spacing positions as determined by the shuttle selectors 190a to 190e, and the transfer cams operate upon the push-pull bars 216a to 216e, to rotate the individual code bars toward marking or spacing positions. Upon the return to normal or upward movement of the transfer assembly the operation is completed; that is, the code bar rotation into marking or spacing positions is completed. The V-members shown on the bottom of the translator housing 213 directly above the transfer cams serve to cam the push-pull bars into the completed movement. The selector transfer assembly in the down and up movement described performs another function; that is, of clearing or resetting the translator stunt bars 214

75 to a normal position in the downward movement, and in releasing all stunt bars for the selection of one stunt bar in the upward movement, by means of the reset disk formed at the top of the transfer frame 192 acting upon the stunt bar extensions about pivot 218. The transfer shift yoke arm is 193 with pivot at 191.

Having described our function selecting mechanism and function performing devices, and the interaction of such previously described mechanism, we are not concerned in the present invention with the structure and operation of the ribbon feed mechanism hereinafter described in detail:

15 Reference is now made to Fig. 4 in which 301 is the ribbon, 302 and 303 are the ribbon reels or spools, 306 and 307 are guides about the reels, and 308 is the mounting plate. Each ribbon reel is provided with an independent transmission 20 system. The transmission for reel 302 comprises ratchet wheel 337, shaft 328, bevel gear 325 in engagement with bevel gear 326, gear 327, and gear 359 (Fig. 6), which is attached to the drive shaft of reel 302. Proper bearings are provided by 320 and 323. The transmission for reel 25 303 comprises ratchet wheel 338, shaft 313, bevel gear 314 in engagement with bevel gear 315, gear 317, and gear 360 (Fig. 6) which is attached to the drive shaft of reel 303. Bearings are provided by 316 and 318.

30 Power for the driving or step forward system is derived from cam shaft 135. As previously mentioned this shaft is connected to the driving motor of the printing telegraph machine by means of a positive clutch in such a manner as to effect one complete revolution of the cam shaft 135 for each complete revolution of the reed escapement distributor shaft. In other words, every complete operation of code group transmission, reception and selection is followed by one complete revolution of cam shaft 135 under motor drive. This cam shaft 135 is equipped with a number of functional cams but we are concerned in this description with the cam 231. This cam is shaped to transmit simple harmonic motion to the cam roller 343 and to the cam rocker arm 340 which is pivoted at 351. The cam rocker arm 340 is mortised to operate upon the intermediate arm 341 which is pivoted at 350. (Fig 5).

35 The spring 342 serves to maintain the reciprocating relationship between the intermediate arm 341, rocker arm 340, and cam 231, by holding roller 343 in engagement with the cam under spring tension.

40 Referring to Fig. 5, the intermediate arm 341 is connected to the vertical drive bar 334, which at its upper extremity is terminated in a slide guide 319. The drive bar 334 is equipped with a drive pawl 335, which is pivoted at swivel 332, seated in catch 348, and a slide fit in the shift guide 339. The drive pawl 335 is provided with a stepping finger shown in Fig. 5 as in engagement with ratchet wheel 338. The spring 345, connected between an extension of the drive pawl 335 and pin 349, is so positioned and tensioned as to hold the drive pawl in the catch seat 348 to which the drive pawl was shifted last. This catch seat 348 is in the form of a double V-block or W. The shift guide 339 is pivoted at 361 and carries a holding dog 347 and associated spring 346. Returning to Fig. 4, the swivel 332 extends shift arms 331 and 333, by means of which the drive pawl 335 and shift guide 339 are shifted from ratchet wheel 337 to ratchet wheel 338, as will be shown hereinafter.

The twin shift levers 329 and 336 are pivoted in members 362 and 363 and are connected together by yoke 330. This combination is maintained in the last set position by the seating action of the depressions in spring 324 on the pin provided on shift lever 329. The actual setting of these shift levers 329 and 336 is the only function and work required of the ribbon in the shifting process. The ribbon 301 is passed through the split stud 304 at reel 302 and through the split stud 305 at reel 303. These studs are connected through slots 355 and 356 in mounting plate 308 (see Fig. 6) to levers 321 and 312 respectively. The levers are pivoted at 357 and 358 and supported in guides 353 and 354. Lever 321 presents pin 322 to shift lever 329, and lever 312 including yoke 309 in guide 311 presents pin 310 to shift lever 336.

The constructional details having been described sufficiently, let us consider the operational features. It will be apparent upon an examination of Fig. 4 that rotation of cam 231 provides the drive for either the transmission connected to ratchet wheel 337, or the transmission connected to ratchet wheel 338, dependent upon which ratchet wheel the drive pawl 335 is engaging. Each vertical thrust of the drive pawl 335 moves the pertinent ratchet wheel one tooth where it is held by the holding dog 347. The shift operation is caused by the eyelet or rivet 364 on the ribbon, attached as standard commercial practice near the end of the ribbon at each reel, attempting to pass through either of the split studs 304 or 305. As shown in Fig. 4, the shift of drive from reel 302 to reel 303 has just occurred.

The ribbon had been winding on reel 302, being drawn from reel 303. Rivet 364 moved split stud 305 and lever 312 to the left. Pin 310 moved shift lever 336 to the position shown. At that instant the drive pawl 335 was in engagement with ratchet wheel 337. Upon the next vertical thrust of the drive pawl 335, shift arm 333 struck shift lever 336, which rotated the drive pawl on swivel 332 from ratchet wheel 337 to ratchet wheel 338, the shift guide 339 and the holding dog 347 moving likewise.

Conversely, when reel 303 is filled and reel 302 presents its ribbon rivet to the split stud 304, shift lever 328 will be moved to the right by pin 322 causing the drive pawl to shift back to engagement with ratchet wheel 337.

Changes, modifications and equivalent arrangements are contemplated within the scope of the invention as defined by the appended claims:

We claim:

1. In a printing telegraph machine, a ribbon feed mechanism comprising a pair of carrying reels; ratchet wheels operative with said reels independently and a swiveled driving pawl alternately operative with said wheels; and means for shifting the driving pawl from engagement with the ratchet connected to the full ribbon reel into engagement with the ratchet connected to the empty ribbon reel; and means including a spring and latch element for carrying through and holding said pawl in each shifted position.

2. In a printing telegraph machine, a type printing assembly which employs a movable ribbon; a ribbon feed mechanism including a pair of ribbon reels and transmission components independently operable with said reels; means including a motor to impart uniform feeding movement to said mechanism; a shift mechanism operative with said components; means including a swiveled

pawl and lever system responsive to ribbon movement to set said shift mechanism in position to reverse the feeding action of the said components; and means acting under power of said motor and not as a function of ribbon movement to cause said pawl to shift from one of said transmission components to the other; and means including a spring element operative with said pawl and a latch seat for holding the pawl in its shifted position.

3. In a ribbon feed mechanism for printing telegraph machines, which employs a printing ribbon and carrying reels therefor; a dual transmission system, comprising components operable independently with said reels; a pawl swiveled to impart step-wise drive to said components alternately; means comprising a system of cams and levers for cyclic operation of said pawl; a motor for operating the cams; a shift mechanism and elements cooperating therewith to position said mechanism for shifting action, said elements being controlled by the feeding movement of said ribbon; and means acting under the drive of said motor and not as a function of the ribbon movement to complete the shifting operation by causing said swiveled pawl to shift from one of said transmission components to the other; said means including a spring element operative with said pawl and a latch seat member for holding the pawl in its shifted position.

4. In a ribbon-feed mechanism for type-printing machines, a pair of reels for carrying the ribbon; drive shafts for said reels; a pair of ratchet wheels disposed in spaced parallel relation and in close proximity to one another; means including a system of gearing operatively connecting shafts and wheels; means for imparting progressive motion selectively to either of said ratchet wheels, said means including a single pawl, and a cam and lever system, said pawl being swiveled and selectively operative between said wheels; and a spring and latch operative with said pawl to retain the pawl in actuated position.

5. In a ribbon-feed mechanism for type-printing machines, a driving system comprising separate components and a ratchet wheel included in each component; a guided thrust member and a swiveled pawl adapted to engage either of said wheels when actuated by said member in response to ribbon movement; and means including a spring element and a latch member operative with the pawl to hold the same in shifted position.

6. In a ribbon-feed mechanism for type-printing machines which employs a pair of reels for carrying the ribbon; a drive system including separate ratchet wheels, a guided thrust member, and a cam and lever system for operating said member; a swivelled pawl adapted to engage either of said ratchet wheels independently, said pawl being provided with oppositely disposed arms; shift levers operable with said arms and means for selectively presenting one of said levers to one of said arms as determined by ribbon movement whereby said pawl is caused to impart driving movement selectively to one of said ratchet wheels.

7. In a ribbon-feed mechanism for type-printing machines, which employs a pair of reels for carrying the ribbon; a dual transmission system including separate ratchet wheels, juxtaposed in parallelism, a guided thrust member, and a cam and lever system for operating said member; a pawl pivoted to engage either of said ratchet wheels independently, said pawl being provided

with oppositely disposed arms for communicating pivotal movement to the pawl; shift levers operable with said arms, and means for selectively presenting one of said levers to one of said arms as determined by ribbon movement and whereby said pawl is caused to impart driving movement selectively to one of said ratchet wheels; and

means including a spring and a double V-member for carrying through and holding the pawl in the last selected position until a reverse selection is required by ribbon movement.

GEORGE A. GRAHAM.
HARRY W. FARMER.
